UNITED STATES PATENT OFFICE.

ALARD DU BOIS-REYMOND, DECEASED, LATE OF PLON, NEAR KIEL, GERMANY; BY ELEONORE DU BOIS-REYMOND, ADMINISTRATRIX, OF HAMBURG, GERMANY, AS SIGNOR TO SIGNAL GESELLSCHAFT MIT BESCHRANKTER HAFTUNG, OF KIEL, GERMANY.

SOUND PRODUCER.

Original application filed April 6, 1923, Serial No. 630,421. Divided and this application filed April 15, 1924. Serial No. 706,792.

To all whom it may concern:

Be it known that ALARD DU BOIS-REYMOND, deceased, late a citizen of the German Republic, residing at Plon, near Kiel, in the Province of Schleswig-Holstein and State of Prussia, Germany, has invented certain new and useful Improvements in Sound Producers, of which the following is a specification.

- 10 This invention relates to sound producers or transmitters, and is a division of application Serial No. 630,421, filed April 6, 1923, Patent No. 1,493,340. The object of the invention is to provide an improved and 15 practicable transmitter of the type operated or actuated by a unidirectional stream of fluid (liquid or gas), and more particularly such a transmitter used for submarine signaling.
- 20 The invention comprises the provision of a sound producer having a mechanical vibratory structure of a definite natural frequency interposed and operating between the fluid discharge nozzle and the 25 sound radiator. The stream of operating fluid is caused to impinge upon the vibratory structure and thus set it in vibration, and the vibratory structure in turn actuates the sound radiator. In the case of a submarine sound transmitter the vibratory structure is so arranged that a transformation 30 of amplitudes of movements takes place between the point where the operating medium impinges on the vibratory structure and the point of connection of the said 35 structure to the radiating member, so that at the last mentioned point the amplitude is smaller than at the first mentioned point. In the case of a transmitter to be used in 40 air the amplitude transformation is in the reverse direction. Of course, more than one vibratory structure may be employed.
- In the accompanying drawing I have shown by way of example a submarine 45 sound transmitter embodying the invention.

Referring more specifically to said drawing, the numeral 1 designates the casing of the transmitter, which is closed by the sound radiating diaphragm 2. A vibratory structure formed of the inelastic masses 3 and 4 connected by the elastic rod 5, is secured to the diaphragm 2 by having the mass 3 directly attached thereto. The con-

duit or tube 7 serves to conduct from any suitable source a fluid under pressure 55 to the vibratory structure to set the latter in vibration. This fluid escapes from the mouth or nozzle 6 of the conduit, impinges upon the mass 4, and flows out of the casting 1 through the outlet pipe 8. 60

The stream of fluid emerging from mouth or nozzle 6 and impinging upon mass 4 sets the vibratory structure 3, 4, 5 in vibration in a manner to be described more in detail hereinafter. This vibration is in turn imparted to the sound radiator 2 which in turn radiates the sound into the propagating medium. 65

As stated hereinbefore, when the invention is applied to submarine sound transmitters a transformation of amplitudes of motion is effected in a downward direction so that the vibrations of the sound radiator, in order to correspond with the sound propagating medium (water), are stepped down to vibrations of extremely small amplitude of movement but of considerable force. This is accomplished in the embodiment illustrated, by having the mass 3 of greater magnitude than the mass 4. The 70 mass 3 includes a portion of the mass of the diaphragm together with a portion of the outside propagating medium which vibrates therewith. 75

The action of the operating fluid in exciting the vibratory structure may be explained in a more or less general way as follows: As the fluid is discharged from the nozzle 6 under pressure it impinges against the adjacent surface of the mass 4. 80 The force of this discharge causes a movement of the mass 3 away from the nozzle and against the elastic force of the elastic member of the vibratory structure. As the mass 4 moves against such elastic force the 85 latter increases. At the same time a decrease in the pressure of the operating fluid occurs as the space between the nozzle and the mass 4 increases and allows the more ready escape of the fluid. Thus a point 90 is reached where the elastic force of the vibratory structure becomes sufficiently great relatively to the pressure in the fluid to cause the mass 4 to move back toward the nozzle 6. As the mass approaches the 95 nozzle the space between it and the nozzle 100

105

is reduced and hence the pressure in the fluid increases. The inertia of the mass causes it to move beyond its position of rest toward the nozzle against the elastic force of the elastic member and the fluid pressure. The increased pressure in the fluid and the elastic force of the elastic member then act to cause the mass to move in the opposite direction away from the nozzle. Thus a periodic movement of the mass toward and away from the nozzle takes place; so that the vibratory structure is set in vibration. The frequency of vibration is dependent among other things upon the individual or natural frequency of the vibratory structure, the pressure of the operating fluid, the form of discharge nozzle, and the space relation between the nozzle and the mass of the vibratory structure. The vibratory structure, it will be observed, acts in the nature of a mechanical interrupter of the fluid flow.

The conduit 7 may be made of such size and shape adjacent the mouth or nozzle 6 as to cause it to act as a resonator and thus reinforce the vibrations.

I claim:—

1. In a sound transmitter, a vibratory structure of definite natural frequency, a sound radiator directly attached to said structure, and means for causing a unidirectional stream of fluid to impinge on said vibratory structure to set it in vibration and thus actuate said radiator.
2. In a sound transmitter, a vibratory structure of definite natural frequency having points adapted to execute different amplitudes of movement, a sound radiator directly attached to said vibratory structure
- 40 at a point having a certain amplitude of

movement, and means for causing a unidirectional stream of fluid to impinge on said vibratory structure at a point having a different amplitude of movement to set the vibratory structure in vibration and thus 45 actuate said radiator.

3. In a submarine sound transmitter, a vibratory structure of definite natural frequency having points adapted to execute different amplitudes of movement, a sound 50 radiator directly attached to said vibratory structure at point having a relatively small amplitude or movement, and means for causing a unidirectional stream of fluid to impinge on said vibratory structure at a point having a relatively large amplitude of movement to set the vibratory structure in vibration and thus actuate said radiator. 55

4. In a sound transmitter, a vibratory structure of definite natural frequency 60 formed of two inelastic masses connected by a distinct elastic member, a sound radiator directly attached to one of said masses, and means for causing a unidirectional stream of fluid to impinge on the other mass to 65 set the vibratory structure in vibration and thus actuate said radiator.

5. In a submarine sound transmitter, a vibratory structure of definite natural frequency formed of two inelastic masses of 70 different sizes connected by a distinct elastic member, a sound radiator directly attached to the larger mass, and means for causing a unidirectional stream of fluid to impinge on the smaller mass to set the vibratory 75 structure in vibration and thus actuate said radiator.
